CURTIS D. CHASE, OF ALLSTON, MASSACHUSETTS, ASSIGNOR TO CHASE HOLDING CORPORATION, A CORPORATION OF PENNSYLVANIA

SNOW MELTER

Application filed October 19, 1927. Serial No. 227,342.

This invention relates to apparatus for melting snow and more particularly to a portable, self-contained apparatus particularly adapted for removing snow from streets, 5 sidewalks and thoroughfares generally.

One of the objects of the present invention is to provide an apparatus of the above general character of simple and practical construction which will be reliable and highly 10 efficient in use and operation.

A further object is to provide a compact, portable, self-contained apparatus adapted to be substantially continuous in its operation.

15 A further object is to provide a compact apparatus of the above character which will be entirely self-contained and which is adapted to utilize the water obtained from melted snow for further melting the snow fed to 20 the apparatus.

A further object is to provide a mechanism of the above general character which may be continuously operated and progressively moved from place to place, as necessary.

25 Other objects will be in part obvious and in part hereinafter pointed out in connection with the accompanying sheets of drawings illustrating a preferred embodiment of the invention and in the several views of which 30 corresponding parts are designated by similar reference characters.

In these drawings—

Fig. 1 is a semi-diagrammatic, longitudinal section in elevation showing such parts of 35 the complete apparatus as is necessary to understand the same;

Fig. 2 is an elevation with a portion in section along the line 2—2 of Fig. 1, looking in the direction of the arrow; and

40 Fig. 3 is a rear elevation looking to the left in Fig. 1.

Referring now to the drawings in detail and more particularly to Fig. 1, 5 indicates a conventional source of power for a tractor, 45 such as a Fordson tractor, adapted to carry at its forward end a snow scoop 6 and a bucket conveyor 7 for raising and discharging snow thru hopper spout 8. These elements form no part of the present invention 50 specifically except in so far as they enter into

the general combination hereinafter set forth and claimed and may be of any desired type and construction. Inasmuch as their operation and use are so well known to those skilled in the art, a detailed description thereof is 55 believed to be unnecessary.

The present invention resides more particularly in that mechanism carried at the rear of the tractor and conveyor unit, which comprises a main supporting frame 10 mounted upon wheels 11 and connected to the tractor unit by the conventional tongue 9, whereby the apparatus may be most conveniently transported from one locality to another. This supporting frame is preferably provided with a plurality of heating units, only two of which are herein shown. The heating units include two relatively large cylindrical chambers 12 mounted in a tank 13. The said units are preferably spaced 60 65 slightly from the bottom of the tank whereby they may be completely surrounded and enclosed by water from the melted snow. The forward end of the chambers 11 are open to a suitable source of heat indicated diagrammatically as fuel oil burners 14 which are supplied from any suitable source of fuel oil and compressed air as indicated by the tank 15. 70 75

The products of combustion from the oil 80 burners 14 pass rearwardly the entire length of the heating chambers 12 into a common header 15, thence forwardly and upwardly thru inclined flues 16 preferably arranged in layers and in staggered relation, as shown 85 more clearly in Fig. 2. The exhaust gases discharge from these tubes into a transverse header 17 from which they pass out thru stacks 18 at each side of the tank 13.

The forward part of the supporting frame 90 10 carries a motor driven pump (not shown) contained within the housing 20 and may be driven either by an independent gas engine or by means of a drive connection 21 taken from the drive shaft of the Fordson. This is a mere mechanical detail and may be varied as circumstances demand. The pump is provided with an inlet pipe 22 at the bottom of the tank 13 and discharges thru a pipe 23 connected with a helical coil 23' in each of the 95 100

heating chambers 12 which in turn discharge to an upwardly and forwardly inclined sprinkling system, shown more clearly in Fig. 2. This system includes two main pipes 24 connecting with the coils 23' and are each provided with communicating cross spray pipes 25 having a plurality of nozzles 26 for directing their streams over the inclined flues 16. The water pumped from the bottom of the tank closely adjacent the heating chambers 12 is highly heated in coils 23' and consequently gives up its heat to melt the snow when it is directed thereupon. Furthermore, the incoming snow from the discharge chute 8, falling upon the tubes 16, which are of course very hot due to the discharge of the products of combustion, will cause the snow to quickly melt and drop thru the pipes into the tank 13. When the water in the tank reaches a predetermined level indicated by the outlet box 27, the excess water is carried off thru a hose 28 to a sewer or the like. When the apparatus is not in use, as when shut down for the day, for example, a cock 30 is opened to drain the tank 13.

In operating the apparatus, it is preferably moved up against a snow pile or drift, indicated at 31, and the conveyor 7 set in motion. In the meantime, however, the burner 14 has been started to thoroughly heat the heating chambers 12 and flues 16. As soon as the snow from the discharge chute 8 falls upon the flues 16, it is either melted or softened to such a degree that it slides down the inclined tubes. When the melted snow collected in tank 13 has reached a depth of several inches, the pump 20 is started to pump the water from the bottom of the tank thru the coils 23' and into the sprinkler system 26 where the streams are forcibly projected against the incoming snow sliding down the highly heated flues. This hot sprinkling feature greatly accelerates the melting action, and thereafter the apparatus is continuously operated as it is progressively moved from place to place, as required.

From the above it is seen that the entire apparatus is portable and self-contained and will operate in a reliable and efficient manner.

Without further analysis the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

I claim:

1. In an apparatus of the character described, in combination, a supporting frame, a tank mounted thereon, a combustion cham-

ber operatively related to the tank, a source of heat therefor, flues in the tank extending upwardly and in inclined relation from the combustion chamber, means for depositing snow on said flues, means for conducting water from said tank through said combustion chamber, whereby to heat the same, a plurality of sprinkler elements disposed in inclined relation above the flues, and means for supplying the sprinkler elements with the heated water. 75

2. In an apparatus for the character described, in combination, a supporting frame, a tank carried thereby, a plurality of heating chambers disposed in the lower part of said tank, a source of heat for said chambers, heating coils in said chambers, a transverse header communicating with said heating chambers, a plurality of upwardly inclined flues having a connection with said header 80 and with an upper header, means for depositing snow on said flues, a sprinkler unit disposed above the flues, and means to deliver water in the tank to the heating coils and thence to the sprinkler unit. 90

3. In an apparatus of the character described, in combination, a supporting frame, a tank carried thereby, a plurality of heating chambers mounted in said tank, heating coils in said chambers, a source of heat for said coils, a transverse header connecting said heating chambers, a plurality of upwardly inclined flues having connection with said header and with an upper header, means for depositing snow on said flues, a plurality of 95 sprinkler elements disposed in inclined relation above the flues, and means to deliver water in the tank to the heating coils and thence to the sprinkler elements. 100

4. In an apparatus of the character described, in combination, a portable frame, a tank carried by said frame, heating chambers mounted in said tank and each provided with a source of heat, heating coils arranged in said chambers, a header with which said chambers are connected, a plurality of flues having connection with said header and extending upwardly therefrom, means for depositing snow on said flues, a pump for drawing water from the tank and connected to 110 the heating coils, and means for directing the water from the coils on to the unmelted snow. 115

5. In an apparatus for the character described, in combination, a portable frame, a tank carried by said frame, heating chambers mounted in said tank and each provided with a source of heat, heating coils in said chambers, a header with which said chambers are connected, a plurality of flues having connection with said header and extending upwardly therefrom, means for depositing snow on said flues, a pump for drawing water from the tank, a connection between the pump and the heating coils, means for directing the 120 water from the coils on to the unmelted snow. 125

water from the coils on to the unmelted snow, an overflow connection on said tank for conducting the excess melted snow from the tank, and means for draining the system 5 when the apparatus is not in use.

Signed at Washington, District of Columbia, this 9th day of September, 1927.

CURTIS D. CHASE.
